HERMANN SCHULTZ, OF BERLIN-LANKWITZ, GERMANY

MOLD FOR ALUMINOTHERMIC WELDING OF RAILS

Application filed December 10, 1928, Serial No. 324,929, and in Germany January 26, 1928.

In the welding of rails by the alumino-thermic method, which involves the pouring of superheated molten metal into a mold enclosing the rail ends and providing a space 5 substantially surrounding the ends of the rails at the top, bottom and sides, it is important to so distribute the molten alumino-thermic metal in the mold that the temperature of the metal shall be as uniform as possible wherever said metal engages the surfaces of the rails to be melted or fused. This has been practically impossible of attainment in the usual standard types of molds employed for this work in which the pouring 10 gates are arranged in the top of the molds and are usually bifurcated or branched to direct the molten metal into the spaces on each side of the rails, so that the molten metal first comes in contact with the rail heads where 15 it gives up a relatively large quantity of heat, the loss frequently being sufficient to prevent the first portion of the pour retaining sufficient heat to melt or fuse those portions of the rail with which it comes into final contact. In other words, the first portion of the molten metal is obliged to traverse the full depth of the mold cavity in contact with the rails to be welded, so that it gives up much 20 of its heat to the upper portion of the rails before reaching the flanges or bases of the rails which it is intended to heat to welding or fusion temperature, in which event it is frequently difficult or impossible to obtain 25 a satisfactory welding of the rail bases or flanges.

The present invention is designed to provide a special form of mold to correct this difficulty and to insure the superheated molten metal reaching all parts of the rail 30 ends to be fused or welded, at substantially the same uniform temperature. The invention is illustrated in the accompanying drawings, in which:—

Fig. 1 is a vertical transverse section through a mold involving the new structural features.

Fig. 2 is a horizontal section on line 2—2 of Fig. 1.

Referring to the drawings, F—F represents the two sections of the mold, formed

of the usual refractory material, adapted to be clamped about the ends of the rails S—S, which are to be welded together, said mold including a central pouring gate b, which is branches or bifurcated at its bottom into channels c, c', which direct the molten metal into the mold cavity to each side of the rail heads, whence it would flow normally in contact with the rail ends through the spaces a, a and ultimately reach the space e, e surrounding the bases or flanges of the rails; with the result that a material part of the superheat of the poured metal would be lost to the upper portions of the rail ends. In order to overcome this difficulty and to insure that the temperature of the molten metal reaching the bases or flanges of the rails shall be of sufficient temperature to fuse or weld the rail flanges together, there are provided in the body of the mold auxiliary channels d, d', which connect the space or portion of the mold cavity adjacent the rail heads directly with the portion of the mold cavity adjacent and surrounding the rail bases or flanges, the said channels being preferably substantially vertical, so that the first portion of the molten metal poured into the mold will divide at the bottom of the pouring gate, be diverted by the channels c, c' laterally toward the sides of the mold cavity adjacent the rail heads, 65 will contact the rail heads only over a limited area, and will then pass down the channels d, d' directly into the portion of the mold cavity e surrounding the bases or flanges of the rails, with a minimum loss of heat. 70

What I claim is:

1. A mold for alumino-thermic welding of rails, in which the portion of the mold cavity adjacent the rail heads is connected to the portion of the cavity adjacent the rail bases by direct channels formed within the body of the mold. 90

2. A mold for alumino-thermic welding of rails, in which the portion of the mold cavity adjacent the rail heads is connected to the portion of the cavity adjacent the rail bases by direct substantially vertical channels formed within the body of the mold. 95

3. A mold for alumino-thermic welding of rails comprising a pouring gate located cen- 100

trally of the top of the mold with divergent channels directed toward the sides of the mold cavity surrounding the rail ends, and auxiliary channels formed and enclosed within in the body of the mold connecting the mold cavity adjacent the rail heads with the mold cavity adjacent the rail bases.

In testimony whereof I affix my signature,

HERMANN SCHULTZ.
